(57) CLAIM

The ornamental design for a wheel cover, as shown and described.

DESCRIPTION

FIG. 1 is a perspective view taken from the left hand side of my new wheel cover; and,
FIG. 2 is a front elevational view thereof.

The broken lines shown in FIGS. 1 and 2 of the drawings are for illustrative purposes only and the subject matter depicted thereby constitutes no part of the claimed design.

1 Claim, 2 Drawing Sheets

FIG. 1

FIG. 2
